UNITED STATES PATENT OFFICE.

RUSSELL STOVER, OF DENVER, COLORADO, ASSIGNOR TO MRS. STOVER'S BUNGALOW CANDIES, OF DENVER, COLORADO, A CORPORATION OF COLORADO.

DESIGN FOR A CHAIR.

Application filed October 18, 1924. Serial No. 11,114. Term of patent 7 years.

To all whom it may concern:

Be it known that I, RUSSELL STOVER, a citizen of the United States, residing at the city and county of Denver and State of Colorado, have invented a new, original, and ornamental Design for Chairs, of which the following is a specification, reference being had to the accompanying drawing forming a part thereof.

The figure is a perspective view of my new design.

I claim:

The ornamental design for a chair, as shown.

In testimony whereof I affix my signature.

RUSSELL STOVER.
